PNEUMATIC SAFETY STOP FOR DIE CLOSURES

Louis H. Morin, Bronx, N. Y.

Application June 10, 1947, Serial No. 753,674

3 Claims. (Cl. 22—92)

1

This invention relates to die casting machines employing pairs of dies movable toward and from each other. More particularly, the invention is concerned with a pneumatically actuated safety stop mechanism whereby the failure of either die to complete its full stroke, or movement into closed position, will set the safety stop mechanism into operation to stop operation of the machine, and further to stop discharge of casting material from the gooseneck or other source of supply. The novel features of the invention will be best understood from the following descriptions when taken together with the accompanying drawing in which certain embodiments of the invention are disclosed, and in which the separate parts are designated by suitable reference characters in each of the views; and in which:

Fig. 1 is a partial sectional view through the die guides and operating mechanism of a casting machine, showing my improved safety stop mechanism in part.

Fig. 2 is a diagrammatic or schematic outline of such parts or mechanisms of a machine as deal with the stop control governed by said safety stop mechanism; and

Fig. 3 is an enlarged detailed view of one of the air valves, showing the same in closed position.

In illustrating one adaptation and use of my invention, I have indicated in Fig. 1 of the drawing, part of a hydraulically actuated die casting machine, such as more fully disclosed in a companion application, Serial Number 753,190, filed June 7, 1947.

In Fig. 1, I have shown at 10, part of a frame of a machine, in which is arranged two similar die guides 11 and 12. In the guides 11 and 12 are slidably mounted die supporting members 13 and 14 supporting on their adjacent surfaces, dies 15 and 16 which are detachable with respect to the members 13 and 14, as by way of plates 17 having screws 19 and 20.

At the outer end portions of the members 13 and 14 are heads 21 and 22 with which are adjustably supported stop screws 23 and 24 adapted to strike blocks 25 and 26 on the guides 11 and 12 in forming a check for inward movement of the dies, and in this respect, said blocks may be composed of cushioning material. Also supported on the heads 21 and 22 are brackets 27 and 28 in which are adjustably supported control screws 29 and 30.

Detachably coupled with the forked extensions 31 and 32 on the frame, are hydraulic cyl-

inders 33—33', both of which are of the same construction, and in said cylinders are arranged pistons or plungers 34—34' adapted to strike blocks 35—35', secured to the outer head ends 21 and 22 of the members 13 and 14 in movement of the dies into closed position. The pistons or plungers 34—34' are actuated by oil, under pressure, introduced into the cylinders through pipes 36—36', both of which communicate with a valve diagrammatically shown at 37 in Fig. 2, which controls the feed of oil under pressure to the cylinders.

In Fig. 2, a pump 38 is shown to pump oil from a supply tank 39 through the valve 37 or back into the tank through a return pipe 40, the latter operating also as a drain for the pipes 36—36'. Extending out from the valve 37 is a plunger carrying a roller 41, by means of which the valve element may be actuated through a suitable mechanism of the machine which forms no part of my present invention and, therefore, is not shown.

In Fig. 2 of the drawing, I have diagrammatically outlined at 42, the pot or molten metal container of the machine in which is swingably mounted the gooseneck 43, the nozzle 44 of which is adapted to be brought into engagement with the dies, one of which is indicated at 15, in Fig. 2. Communicating with the gooseneck 43 is an air line 45 in which is disposed an electrically controlled and operated valve 46, so that as and when the circuit to the valve 46 is broken, the air supply to the pipe 45 will be shut off, preventing discharge of molten metal to the gooseneck.

Supported on top of the guides 11 and 12 are valve devices 47 and 48 in which are mounted plungers 49 and 50 normally held in outwardly extended positions by springs 51 and 52. An air supply pipe 53 has communications centrally of the cylinders 47 and 48, as at 54 and 55, and at the end of the cylinders communicate pipes 56 and 57, the latter having one communication, as at 58, with a pipe 59. One end of the pipe 59 extends to a diaphragm valve 60 and the other end to a plunger pin operating device 61, the pin 62 of which is adapted to support an arm 63 in such position as to maintain the gooseneck 43 with the nozzle 44 out of engagement with the dies. The pin 62 thus renders a cam 64, normally controlling operation of the lever 63, inoperative.

The diaphragm valve 60 has a plunger pin 65 for actuating a suitable switch, as at 66, to break the circuit through the wires 67 and 68. In Fig. 55 2, 69 diagrammatically illustrates the motor for

actuating the machine. In Fig. 1, means such as the hydraulic actuated plungers 34—34' are shown for moving the dies into closed position, other means being employed for moving the dies into open position, but such means is not shown, as it forms no part of the present invention but is clearly shown in the application above referred to.

The present invention is concerned primarily with movement of the dies into abutting engagement with each other, and in holding the dies in such engagement. This is accomplished by the hydraulically actuated plungers and in inward movement of the dies by the plungers. The control screws 29 and 30 strike the plungers 49 and 50 and advance said plungers inwardly to a point where they cover the discharge ports 54 and 55, providing each die has fully completed its closing movements. Immediately after the dies have completed the closing movement thereof a blast of air pressure is admitted into the pipe 53, and if the plungers 49 and 50 are in their closed position, this air will be checked at the valves 47 and 48. However, should either one of the dies fail to complete its inward or closing movement, this would result in failure of the associated plungers 49 and 50 to close the port 54 and 55, thus allowing air under pressure to pass through one of the pipes 56 and 57 and into the pipe 58 and thus extend to the valve 60 and the device 61. It will appear that operation of the valve 60 will break the circuit through the switch 66, stop the motor, and at the same time, release the valve 46 to close the same, preventing air from timely entering the pipe 45. The actuation of the device 61 provides a further safeguard in maintaining the nozzle 44 out of engagement with the dies.

The control screws 29 and 30 provide a fine adjustment for the actuation of the plungers 49 and 50 so that closing movement of the dies can be carefully gauged.

In operation of dies of the type and kind under consideration, it is also possible that some foreign material may present itself between adjacent surfaces of the dies preventing the dies from performing the full stroke which would insure complete closure of the dies. It is also possible that some mechanism may present itself between the head ends of the members 13 and 14, and the guides therefor, which would check inward movement, or further that the hydraulic cylinders may fail to perform their intended function. With my improved safety stop control of die closure, operation of the machine will be checked and discharge of casting material stopped until necessary repairs have been made to facilitate proper functioning of the dies.

It will be understood that my invention is applicable to machines of the general type and class under consideration wherein a pair of dies are movable toward and from each other.

In machines of the type and kind under consideration it has been customary to employ control switches which are constantly operated in each cycle of operation of the machine. This results in a wear which requires replacement of the switches from time to time. One of the distinctive features of my invention resides in the fact that during normal operation of the machine, the switch 66 remains closed and the switch operating mechanism idle. It is only when a die fails to properly close that said mechanism and switch are put into operation.

Having fully described my invention, what I

claim as new and desire to secure by Letters Patent is:

1. In a pneumatic safety stop mechanism for stopping the operation of a die-casting machine upon failure of either one of a pair of movable dies in said machine to complete its closing movement, said dies being slidably supported in guides on the frame of the machine and being movable toward and away from each other, the combination of a switch controlling the operation of the machine, and operated by a pneumatic means a pneumatic control valve supported in a fixed position on each of the guides, said control valves normally being open and having an outlet port connected to the pneumatic operating means of the switch and an inlet port connected to means for intermittently supplying air under pressure from a common source to each of said valves, and valve-operating means carried by each of the movable dies, each of said valve-operating means carried by the respective dies engaging with and closing one of said control valves upon movement of its respective die to closed position.
2. In a pneumatic safety stop mechanism for stopping the operation of a die-casting machine upon failure of either one of a pair of movable dies in said machine to complete its closing movement, said dies being slidably supported in guides on the frame of the machine and being movable toward and away from each other, the combination of an electric motor for actuating the machine, an electrically operated valve controlling the admission of air under pressure to means for discharging molten metal to the dies, a circuit connecting said motor and said valve to a source of electrical energy, a switch in said circuit, said switch being normally closed and being operable by pneumatic means to open said circuit, a pneumatic control valve supported in a fixed position on each of the guides for the dies, said control valves normally being open and having an outlet port connected to the pneumatic operating means of the switch and an inlet port connected to means for intermittently supplying air under pressure from a common source to each of said valves, and valve-operating means carried by each of the movable dies, each of said valve-operating means carried by the respective dies engaging with and closing one of said control valves upon movement of its respective die to closed position.
3. In a pneumatic safety stop mechanism for stopping the operation of a die-casting machine upon failure of either one of a pair of movable dies in said machine to complete its closing movement, said dies being slidably supported in guides on the frame of the machine and being movable toward and away from each other, the combination of an electric motor for actuating the machine, a circuit connecting said motor to a source of electrical energy, a switch in said circuit, said switch being normally closed and being operable by pneumatic means to open said circuit, a pneumatic control valve supported in a fixed position on each of the guides for the dies, said control valves normally being open and having an outlet port connected to the pneumatic operating means of the switch and an inlet port connected to means for intermittently supplying air under pressure from a common source to each of said valves, and valve-operating means carried by each of the movable dies, each of said valve-operating means carried by the respective dies engaging with and closing one of said control valves upon movement of its respective die to closed position.

upon movement of its respective die to closed position.
